UNITED STATES PATENT OFFICE.

EDWARD N. TRUMP, OF SYRACUSE, NEW YORK, ASSIGNOR TO THE SOLVAY PROCESS COMPANY, OF SOLVAY, NEW YORK, A CORPORATION OF NEW YORK.

GAS-PRODUCER.

No. 893,114.

Specification of Letters Patent.

Patented July 14, 1908.

Application filed June 1, 1907. Serial No. 376,634.

To all whom it may concern:

Be it known that I, EDWARD N. TRUMP, a citizen of the United States, residing at Syracuse, in the county of Onondaga and State of New York, have invented a new and useful Gas-Producer, of which the following is a specification.

My invention relates to improvements in gas producers.

10 My object is to provide improved means for the discharge of the ash therefrom.

My invention comprises improvements in the structure shown in patent to me No. 813,600 dated Feb. 27, 1906, and relates especially to means for the supporting, guiding and actuating of the discharging knife or knives adapted to sweep the stationary table or platform spaced below the lower end of the gas producer chamber.

20 Referring to the drawings: Figure 1 is a vertical cross section of a producer showing my improvement. Fig. 2 is a partly broken plan view on an enlarged scale. Fig. 3 is a vertical section on line 3, 3 of Fig. 2. Fig. 4 is a similar view showing roller bearings instead of ball bearings. Fig. 5 is a similar view showing a plain or sliding bearing for the knife supporting structure.

Similar numerals refer to similar parts throughout the several views.

In Fig. 1, I show in section the gas producer similar to that shown in my patent above referred to, in which the table 6 is stationary, while the knives 7 and 8 extend 35 across the table from center to periphery and are caused to rotate to sweep the same. These knives are shown as curved so as to present the desired working face similar to that previously described, in my above mentioned patent. It is obvious however, that other forms of knife may be used without departing from the spirit of this invention.

In Figs. 2 and 3, I have shown more in detail the arrangement of the moving parts. 45 The knives 7 and 8 are given a hook formation so that they will engage about the collar 9 forming part of the twyer structure, or fixed blast pipe 10. This collar 9 is provided with a flange 11 which projects over 50 the hook ends of the knives 7 and 8, and cooperates in maintaining the desired vertical position of said knives with respect to the table. The outer ends of knives 7 and 8 are bolted to brackets 12 and 13, which in turn.

are part of or secured to the circular plate 55 structure 14 beneath the stationary table 6. This supporting plate 14 surrounds the stationary drum 15 of the framework which supports the table or platform 6. A channel is formed beneath the stationary platform 6 by the annular projections or ribs 16. In this channel are seated a series of anti-friction balls 17 for engaging the upper side of the plate 14. The annular rib 18 projecting downwardly from the underside of plate 61 14 cooperates with the stationary supporting structure 15 to form a second annular channel to receive the anti-friction balls 19. Thus is formed a ball bearing support for the rotating supporting plate 14 beneath the stationary platform 6, and in connection with the foundation parts of the producer. Beneath the supporting plate 14 at the outer periphery thereof, is secured the beveled gear 20 adapted to cooperate with the beveled pinion 21, operated through the worm gear 22 from any suitable source of power.

In Fig. 4, I show substantially the same construction with the exception that, in lieu of the anti-friction balls 18 and 19, I have substituted the antifriction beveled rollers 23 and 24. While in Fig. 5 I show a further modification that is, in lieu of the anti-friction balls or rollers, I provide a simple or plain sliding bearing between the supporting 85 plate 14 and the stationary parts.

The knives may be used either singly or double, and operate to sweep out from under the mass or column of ashes and coal a uniform section of the ashes, which may be varied by the taper of the knife from toe to heel.

The movement of the knife causes the cylinder of material above to drop down uniformly over the whole area, and as the arch of material behind the knife falls it causes the descent of the wedged shaped portion, to the top of the mass, and thus keeps the whole bed of coal in movement, leaving it porous and free from coke or clinker masses, and without holes.

What I claim is:

1. In a gas producer, comprising a stationary table spaced beneath the lower edge of the producer chamber, a deflector member 16 adapted to sweep said table and a supporting structure therefor, connected with the outer end of the deflector, comprising a rotatable

member located beneath the table having a bearing in the supporting stationary framework of the producer.

2. In a gas producer, the combination of a combustion chamber, a fixed table spaced below the lower extension thereof, a deflector projecting over the table from the periphery toward the center, and a deflector-supporting member connected therewith outside the periphery of the table, having its bearing in the stationary structure beneath the table.

3. In a gas producer, the combination of a combustion chamber, a fixed table spaced below the lower extension thereof, a deflector projecting over the table from the periphery toward the center, and a deflector-supporting member connected therewith outside the periphery of the table, having an anti-friction bearing in the stationary structure beneath the table.

4. In a gas producer, the combination of a combustion chamber, a fixed table spaced below the lower extension thereof, a deflector projecting over the table from the periphery toward the center, and a deflector-supporting member, connected therewith outside the periphery of the table, having an anti-friction ball bearing in the stationary structure beneath the table.

5. In a gas producer, the combination of a stationary table spaced beneath the producer chamber, a deflector for sweeping the table, a revolving member having a bearing in the stationary structure beneath the table, and means for connecting said revolving member with the deflector outside the periphery of the table.

6. In a gas producer having a fixed blast pipe, the combination of a stationary table spaced beneath the producer chamber, a deflector for sweeping the table, means for journaling the deflector at the center of the table about the fixed blast pipe and means for applying power to the deflector beyond the periphery of the table.

7. In a gas producer, the combination of a stationary table spaced below the producer chamber, a deflector for sweeping the table, rotating means beneath the table, a bracket

carried thereby, means connected with the outer end of the deflector and beyond the periphery of the chamber for rotating the deflector, and means for controlling the vertical position of the deflector near its axis of rotation.

8. In a gas producer, the combination of a stationary table spaced beneath the producer chamber, a deflector for sweeping the table, having its end toward the center of the table curved, and a centrally located fixed bearing for the curved end of the deflector.

9. In a gas producer, the combination of a stationary table spaced below the producer chamber, a deflector for sweeping the table, having its end toward the center of the table curved, a centrally located fixed bearing and keeper for the curved end of the deflector, a rotating member and means for connecting the outer end of the deflector therewith.

10. In a gas producer, the combination of a stationary table spaced below the producer chamber, a pair of oppositely extending deflectors for sweeping the table, having their ends toward the center of the table curved, and a centrally located fixed bearing for operating with said curved ends.

11. In a gas producer, the combination of a producer chamber, a table spaced below the chamber, a deflector for sweeping the table and means for actuating the deflector comprising a rotating structure supported beneath the table, and means for connecting the same with the end of the deflector beyond the periphery of the table.

12. In a gas producer, the combination of a producer chamber, a table spaced below the chamber, a deflector for sweeping the table and means for actuating the deflector comprising a rotating structure supported beneath the table on anti-friction bearings and means for connecting the rotating structure with the end of the deflector beyond the periphery of the table.

EDWARD N. TRUMP.
